UNITED STATES PATENT OFFICE.

REUBEN W. DREW, OF CLEVELAND, OHIO.

FURNACE-FEEDING DEVICE.

SPECIFICATION forming part of Letters Patent No. 247,469, dated September 20, 1881.

Application filed January 12, 1881. (No model.)

To all whom it may concern:

Be it known that I, REUBEN W. DREW, of Cleveland, county of Cuyahoga, State of Ohio, have invented certain new and useful Improvements in Furnace-Feeding Devices, of which the following is a specification.

My invention relates to improvements in apparatus for mixing currents of steam with currents of air and introducing the same when thoroughly mixed into the flame-chamber of the furnace. It also consists in the combination and arrangements of the several parts or elements hereinafter particularly described.

The objects of my invention are to produce means for causing steam and air to become thoroughly mixed and discharged in diffusive subdivided streams or currents into the flame-chamber of furnaces for the better and more perfect combustion of the combustible gaseous products evolved from the top surface of the fuel, which heretofore escaped unconsumed; also for adjusting and regulating the proportions of steam and air to be mixed and jointly introduced into the flame-chamber of the furnace, so as to better adapt the apparatus for use with any of the various kinds of fuel employed for combustion in furnaces. I attain these objects by means of the mechanism illustrated in the accompanying drawings, in which—

Figure 1 represents a sectional elevation of the apparatus, except the blower. Fig. 2 is a plan view of the face of the spreader. Fig. 3 is a cross-sectional view taken at line No. 1 in Fig. 1. Fig. 4 is a cross-sectional view taken at line No. 2 in Fig. 1. Fig. 5 is a cross-sectional view taken at line No. 3 in Fig. 1. Fig. 6 is a side elevation of the gaging-pin and its gaging-groove. Fig. 7 is a cross-sectional view of the gaging-pin, taken at line No. 4 in Fig. 1. Fig. 8 is a side elevation of the apparatus, illustrating the same in position and in connection with the furnace.

Similar letters refer to similar parts throughout the several views.

In the drawings, A represents a section of the furnace of a boiler, and A' is the heated portion of the same, to which my improved apparatus is attached, as shown in Fig. 8. B is a shell-form bracket, which bracket is secured in connection with the furnace at a

point above the upper plane of the upper surface of the fuel on the grate of the same by means of a short screw-connection pipe. The said bracket holds and supports the operating parts of my improved apparatus, and is provided with an interior chamber, B', made, preferably, in a spherical form. The upper side of this chamber is closed by the screw cap or plug C. The rear side of said chamber is provided with opening a, which communicates through the screw-connection pipe b with the combustion-chamber of furnace A. Made opposite of opening a is opening a', closed by screw-plug D, which screw-plug terminates with a steam-pipe, D', which pipe holds and supports some of the operating parts of my improved device within chamber B'. Made in the lower side of bracket B is opening a², the mouth of which is provided with a screw-thread for connecting the said bracket and its chamber B' with the air-tube E, which air-tube connects with a blower, E'.

The screw-plug D is recessed in its front end and provided with a screw-thread, e, for connecting bracket F with bracket B. The said bracket F contains the steam-chamber F', which chamber has an opening, e, above, provided with a screw-thread for connection with a steam-pipe, G, connecting with the boiler (not shown) for the introduction of steam to said chamber. Placed opposite said opening e is opening e', provided with a screw-thread for connection with a blow-cock, H. Connecting with the rear side of the said steam-chamber is opening e², and with the front side of said chamber is the opening e³, which latter opening is closed with screw-plug I.

The steam-pipe D', attached to screw-plug D, is extended rearward from opening a' about centrally through chamber B' to a short distance from the throat of opening a, as shown in Fig. 1. The rear end of said steam-pipe is made with a funnel-shaped end opening, m, which connects with the bore f of said steam-pipe. Fitting in the said funnel-shaped opening m is the steam-spreading plug M, which plug is made conical to correspond with said funnel end opening, and is furnished with a series of grooves, n n, running in spiral directions from the apex of said plug to its base, as shown in Fig. 7. The small end of the

cone-plug M is made to terminate in a cylindrical nib, n', provided with a screw-thread, which nib screws into a corresponding screw-thread cut in the bore f of the steam-pipe D', and holds the said conical plug in secure connection with the funnel end m of the said steam-pipe. Grooves n are formed in the periphery of the screw-threaded nib n' for connection of the chamber B' with the bore f of the steam-pipe D'. The funnel end m of said steam-pipe, together with the conical plug M, provided with grooves n, form what I denominate the "steam-spreader."

Projecting rearward from the base of the conical plug M is the spindle N, on which freely revolves a fan-draft wheel, O, which wheel sets in the throat of opening a, as shown in Fig. 1.

The rearend of the plug D is centrally pierced in direction of its length, and in a line coincident with the axis of the bore f of steam-pipe D', with a bore, f', of smaller diameter than that of bore f, so as to form a connection of said steam-pipe with the steam-chamber F'. The said bore f' is provided with a screw-thread, s.

The screw-plug I of the steam-chamber F' is centrally pierced in a line of direction coincident with the line of direction of the screw-threaded bore f made in the screw-plug D.

Passing through the pierced plug I, and centrally through the steam-chamber F', and screwing into the screw-threaded bore f', is the steam-gaging pin P, provided with a finger-wheel, P', by which said gaging-pin may be operated, so as to be screwed to any distance into bore f', as may be selected. Cut into one of the sides of the said gaging-pin and into its screw-threaded end portion is a gaging groove or recess, q, made, preferably, with V-shaped form of sides from the periphery of said pin, and with a gradually-tapering form in direction of its length, with the base or wide end of the groove terminating in the plane groove q', made in the end portion of the gaging-pin, and at its point or apex terminating at a distance from the extreme end of said gaging-pin about equal to the length of the screw-threaded bore, into which the said pin works. A stuffing-box 50 may be made with plug 1, so as to make the joint of the gaging-pin with said plug steam-tight. The screw-thread s of bore f' and the screw-thread of the said gaging-pin working in said screw-threaded bore may be omitted, and a screw-thread cut on the gaging-pin at its finger-wheel end and working into a screw-threaded hole made in the plug may be substituted.

The manner in which the several parts of my improved apparatus for mixing and forcing air and steam into furnaces operate is as follows: One or a series of the said apparatuses are attached to the furnace to be supplied with mixed air and steam, according to the size of the furnace and the capacity of the apparatus. The air-conductor E is connected with the blower,

and the steam-pipe G is connected with the boiler, when the apparatus is ready for operation. Before the steam is permitted to escape from chamber F' into chamber B' the communication between said chambers is to be temporarily closed by screwing the gaging-pin P inward, when the operator will turn the key of blow-cock H so as to discharge the waste-water and sediment which may have accumulated within the said steam-chamber and the steam-pipe. The blow-cock will then be closed, and the gaging-pin will be screwed outward, so that the gaging-groove q in said gaging-pin will have a portion of its length drawn back into the throat c' of steam-chamber F', so that said groove will afford a free communication between the bore f of pipe D and chamber F' for the passage of steam from the latter to the former. When it is selected to have a greater quantity of steam admitted the gaging-pin will be turned outward, so as to draw the widest portion of the gaging-groove q to the throat c' of chamber F'; and when a less quantity of steam is to be employed the said pin will turn in, so that the more contracted portion of the groove will be at the said throat, and accordingly as the area of said gaging-groove in its enlarged or contracted portions are brought to the throat of the steam-chamber the quantity of steam admitted to bore f will be increased or lessened. The bore f of pipe D' conducts the steam to the spreader M m, and, entering the spiral grooves n, made with the conical plug M, will escape into chamber B'. The said steam-spreader, by reason of its conical form, operates to cause the current of steam to escape into chamber B' in lines of direction at an angle with the line of direction of the bore f; or, in other words, the current of steam will be made to be funnel shape or conical and diffusive instead of compacted and solid, as heretofore produced. By means of the grooves n made with the spreader the steam is made to escape into chamber B' in numerous small streams or currents, moving with high velocity in lines of direction which will be divergent in their character, and by forming the said grooves spiral each of the streams will be made to become not only divergent in their character, but will be made to twirl more or less in their escape into said chamber. The steam escaping from the spreader enters into the throat a of the chamber B' with great velocity, and drives before it the air that may be in front, and tends to create a vacuum in the air-pipe E, and the pressure of the outside atmosphere will force the air forward in said pipe to replace the air in chamber B' as it is being expelled by the force of the currents of steam from the spreader. The steam-current and the air-current together will strike the fans of the revolving draft or outlet wheel O and cause said wheel to revolve with high velocity, and together pass into the throat of the discharge-opening a, through the spaces between the fans of said wheel. The said wheel, freely revolving within the said dis-

charge-opening, offers no impediment to the passage of the steam and air escaping through the spaces of the fan-wheel, while the said spaces will be quickly rotated and cause the mingled steam and air to have its several points of entrance continuously changing in a rotating manner, so as to give to the current a twirling movement, which will thoroughly mix the steam and air in a manner not heretofore practiced. The fan-blower E' will exert a pressure on the air in the air-supply pipe E, and will force a blast of air into the mixing-chamber B', and the discharge-opening a, being of smaller capacity than that of the said air-supply pipe, will somewhat check the free escape of the air from said mixing-chamber, and thereby cause the air within the same to be more dense than it would be if the discharge-opening were of the same capacity, so that when the steam is discharged forward it will carry with it a larger quantity of air than is possible without the employment of the blower.

When it is desired to cause air to be introduced in greater excess of steam the operator will set the gaging-pin P inward to a point which will reduce the volume of steam to be discharged into the mixer, while, when it is desired to have the steam largely in excess of the air, the gaging-pin P will be drawn back so as to enlarge the opening for the passage of the steam from the steam-chamber, while at the same time the fan-blower will be made to operate with less force, or may be wholly stopped. In the latter case the air will be drawn through the air-supply pipe into the mixing-chamber by the draft caused by the discharge of the steam into the discharge-opening of said chamber.

It will be readily observed that by my improvements proportions of steam and air mingled together and discharged into the flame-chamber of the furnace can be readily and nicely adjusted and regulated.

It will also be readily observed that the steam will be made to have a diffused discharge into the mixing-chamber instead of a concentrated discharge, as heretofore, and that the escape of the steam into the said chamber will

be in small streams or currents which are divergent in their character, and also have given 50 to them, or each of them, a direction of movement which will be more or less spiral in its nature, while the revolving spaces or escape-openings in the fan will give to the current of mixed steam and air a twirl which will complete the mixing of the said two elements before their final discharge into the flame-chamber of the furnace.

To render the steam-pipe D' capable of being extended in its length so as to cause the 60 discharge end of the spreader to be adjusted to any point nearer to the throat of the opening a of the mixing-chamber, the pipe D' is made sectional and the sections are held in connection by means of sleeve D², as shown in Fig. 65 1, and set-screws or screw-threads cut on the neighboring ends of the sections of pipe D' and in the bore of the sleeve may be employed.

Having described my invention, what I claim, and desire to secure by Letters Patent, is— 70

1. In a furnace-feeding device, the combination, with a mixing-chamber, air-supply pipe, and steam-supply pipe, of a steam-spreader and a revolving outlet-wheel set into the throat of the discharge-opening of said mixing-chamber, for the purpose set forth. 75

2. In a furnace-feeding device, the combination, with a mixing-chamber, air-supply pipe, and steam-supply pipe, of a spreader formed by the conical end opening, m, and conical plug 80 M, having a space or spaces between for the escape of the steam thus spread into the mixing-chamber, and a revolving outlet-wheel in the discharge-throat, as and for the purposes set forth. 85

3. In a furnace-feeding device, the combination, with a mixing-chamber, a steam-chamber, and a pipe, D', connecting the two, of a gaging device for regulating the quantity of steam let into said pipe D', and the spreader M m n, for 90 diverging or spreading the same in the mixing-chamber, as set forth.

REUBEN W. DREW.
